UNITED STATES PATENT OFFICE

FRITZ WERSEBE, OF HAGEN, GERMANY

SMOKER'S ASH RECEPTACLE

Application filed February 2, 1929, Serial No. 337,151, and in Germany December 14, 1927.

This invention relates to smokers' ash receptacles and consists in the provision of a casing formed with a hopper which is normally closed at the bottom by two arcuate, pivotally supported plates adapted to turn in opposite directions about pivots arranged in the lower part of the casing in the centre of the plate curvature for opening and closing the hopper, the plates being arranged relative to overhanging hopper walls so as to be swept by the latter for clearing off the ashes, means being provided for maintaining the plates normally in closed position and for opening out the same by the depression of an operating element.

Fig. 1 of the accompanying drawings represents a vertical section of one form of the device,

Fig. 2, a vertical section of another form,
20 Fig. 3, a section on the line III—III of Fig. 2,

Fig. 4, a vertical section of a further modification, and

Fig. 5, a section at right angles to Fig. 4.
25 The ash receptacle comprises a casing 1 the sides 2 of which may either be upright or slanting and adapted to receive advertisements. In the top wall of the casing there is an opening 3 and under the latter there is a hopper 4 the bottom of which is normally closed by two arcuate plates 5 and 6. These plates are supported by arms 9 and 10 which are pivoted at 8 near the bottom 7 of the casing; the pivots being concentric with the plates. The plates are weighted by bars 11 which tend to hold them together and keep the hopper closed. The inner edges 12 of the plates are turned up for engagement with the overhanging hopper walls which are adapted to sweep the plates so as to clear them of ashes when the plates are turned back for opening the hopper. For a convenient opening out of the plates, a key 14 is provided the stem of which is guided in a sleeve 13 and in a bracket 29 and connected by links 15, 15' to the arms 9 and 10 so that the latter will be pressed apart on the depression of the key. A spring 16 on the key stem tends to raise the key and aids the

50 weights 11 to keep the hopper closed.

For discharging the ashes from the casing, one side wall is provided with an aperture which is normally closed by a cover 2' fitted with a handle 18. A spring 17 bears against a flange on the cover so as to retain the latter in closed position.

The ash receptacle is surmounted by a match box support in the form of a platform 20 which is carried on the casing by legs 19. The match box holder 22 is provided with two resilient arms 21 and with springs 24 which are formed with nicks 23 for engagement with apertures in the platform 20. These springs enable the match box holder to be detached from the platform. The holder has also a U-shaped, upwardly directed shackle which is adapted to be inserted into the match box cover. If this insertion is effected after the end wall of the drawer has been detached, it is possible, after the insertion, to remove the drawer and leave the matches conveniently supported in the cover and in the shackle.

As an alternative, the holder 22 may be adapted for insertion into the match box cover without the shackle which may then be dispensed with.

The construction shewn in Figs. 2 and 3 is similar to the one already described, the only difference being that the casing is provided with a detachable top cover 27 which is adapted to carry the entire mechanism, the pivots 8 being connected to brackets 28 which depend from the cover. In this case the cover and the mechanism are removed together from the casing for entering the latter. The cover has a downturn rim 26 which fits over the edge of the casing and which may be punched with depressions 33 for engagement with corresponding projections on the casing. In addition, a spring catch 32 may be employed for holding the cover normally in position. There are two key stems 31 for operating the plates 5 and 6 and these stems, which are guided in apertures 30 in the cover, are interconnected by a bridge piece 19' which carries the match box holder.

A suitable arrangement for use in motor cars and the like is shewn in Figs. 4 and 5.

As the casing in this instance requires to be small, the arms 9 and 10 are adapted to turn about the same axis 35, the plates 5 and 6 being turned from a substantially horizontal into a substantially vertical position, as shewn in Fig. 4.

The cover 27, which carries the entire mechanism as in the previous construction, is connected to a plate 34 whereby it is secured either to the dash board or to some other part of the vehicle, the casing being withdrawable from underneath. Spring catches 36, connected to the brackets 28, are adapted to engage under shoulders on the casing so as to retain the latter normally in position.

I claim:

1. A smoker's ash receptacle comprising a casing formed with a hopper, two arcuate plates adjoining overhanging hopper walls and forming a bottom for the hopper, pivoted arms supporting said plates in the lower part of the casing so as to allow them to turn in opposite directions about the centre of the curvature for opening and closing the hopper, the plates being arranged relative to the overhanging hopper walls so as to be swept by the latter, means for maintaining the plates normally in closed position, and an operating element adapted, on depression, to open out the plates.

2. A smoker's ash receptacle comprising a casing, a detachable cover for said casing provided with a hopper, two arcuate plates adjoining overhanging hopper walls and forming a bottom for the hopper, a pair of supporting brackets depending from the cover, supporting arms for the plates pivoted to said brackets so as to enable the plates to turn in opposite directions about the centre of the curvature for opening and closing the hopper, the plates being arranged relative to the overhanging hopper walls so as to be swept by the latter, means for maintaining the plates normally in closed position, and an operating element linked to said arms and adapted, on depression, to open out the plates.

3. An ash receptacle as claimed in claim 2 wherein the plates are adapted to turn about a common axis from a substantially horizontal to a substantially vertical position.

4. An ash receptacle as claimed in claim 2 and means for fastening the cover to a wall and for locking the casing to the cover.

5. The ash receptacle claimed in claim 2 in combination with a platform, legs supporting said platform on the casing, and a match box holder detachably mounted on said platform.

6. The ash receptacle claimed in claim 2 in combination with a platform, legs supporting said platform on the casing, and a match box holder adapted to be inserted into

the match box cover and to be detachably secured to said platform.

7. The ash receptacle claimed in claim 2 in combination with a platform, legs supporting said platform on the casing, a match box holder, and nicked supporting springs connected to said holder and adapted to engage in slots in the platform for retaining the holder on the latter.

FRITZ WERSEBE.
